BALANCED ELECTRON TUBE CIRCUITS

Walter Soller, Tucson, Ariz., assignor of one-half
to William H. Woodin, Jr., Tucson, Ariz.

Application September 9, 1933, Serial No. 688,833

17 Claims. (Cl. 175—183)

My invention relates broadly to electron tube circuits and more particularly to the use of electron tube devices in measuring and amplifying electric voltages and currents.

One of the objects of my invention is to provide a balanced single electron tube circuit for the precision measurement of ionization and other infinitesimal electron currents.

Another object of my invention is to provide 10 an electron tube circuit arrangement wherein the output may be taken from any two elements of the electron tube thereof.

Still another object of my invention is to provide 15 a balanced electron tube circuit for the amplification of direct and alternating currents and voltages.

A further object of my invention is to provide 20 a multi-stage electron tube amplification system for signal receiving circuits having means for precisely balancing each of the electron tube stages.

A still further object of my invention is to provide 25 a system of balancing a multi-stage amplification system employing screen grid electron tubes, which involves the disposition of resistors of selected value between the output circuit of one electron tube and the input circuit of a succeeding electron tube in such arrangement as to balance the operation of the circuits.

Another object of my invention is to provide 30 a circuit arrangement for a multi-tube amplification system operative to amplify either direct or alternating current and in which special arrangements and values of resistors are employed for coupling the output system of one tube with the input system of a succeeding tube while insuring balanced operation thereof.

Still another object of my invention is to provide 35 a circuit arrangement for a screen grid multi-tube amplifier system with a balanced bridge circuit including resistors of selected values in selected arms thereof for effecting a balanced transfer of energy from the output of one screen grid tube to the input of a succeeding screen grid tube.

A further object of my invention is to provide 40 a circuit arrangement for a measuring instrument which includes an electron tube employing an additional grid element connected in balanced relation to an output meter for effecting the precision measurement of minute currents or voltages.

A still further object of my invention is to provide 45 an improved light sensitive cell control circuit having means for freeing the light sensitive

cell from variations in line voltages by precision balancing of the electron tube circuit.

Other and further objects of my invention reside in the electron tube circuit arrangements as set forth in the specification hereinafter following, by reference to the accompanying drawings in which:

Fig. 1 is a diagram of the circuit arrangement of my invention as applied to a galvanometer type of measuring apparatus; 10

Fig. 2 is a graph showing the anode current versus filament current characteristics of different tubes tried in the measuring circuits of my invention;

Fig. 3 is a diagram of a circuit arrangement for 15 an electrometer type of measuring system embodying my invention;

Fig. 4 is a diagram of the balanced electron tube circuit of my invention as applied to a measuring instrument adapted to be energized 20 from a direct current power supply;

Fig. 5 is a circuit diagram of a balanced electron tube system embodying my invention and in which the voltage applied to the screen grid is equal to the voltage impressed upon the plate. 25

Fig. 6 is a circuit diagram of a balanced electron tube system embodying my invention and in which the voltage applied to the screen grid is equal to the voltage impressed upon the plate;

Fig. 7 is a circuit diagram of a balanced electron tube system embodying my invention and in which the voltage applied to the screen grid is greater than the voltage impressed on the plate; 30

Fig. 8 is a circuit diagram of a balanced electron tube system embodying my invention and in which the voltage applied to the screen grid is greater than the voltage impressed on the plate; 35

Fig. 9 is a diagram of the circuit of my invention as applied to the amplification of alternating currents or pulsating direct currents and adapted to be energized from an alternating current power supply. In this circuit, as in the other circuits shown in Figs. 10 and 11, where 40 alternating current is the power supply, heater type screen grid tubes are employed wherein the cathode is brought to operating temperature by the heater element shown at 22 and energized from the transformer coil shown at 33; 50

Fig. 10 is a diagram of the circuit of my invention as applied to the amplification of steady direct currents and adapted to be energized from an alternating current power supply; and

Fig. 11 is a diagram of the balanced circuit of 55

my invention in conjunction with a light sensitive cell.

5 My invention comprises a single-tube balanced circuit which has all the advantages of the two-tube balanced circuit without extra equipment and eliminates most of the tedious manipulations necessary in that circuit to obtain a balance. I have obtained accurate measurements by the use of the circuits of my invention in the measurement of currents smaller than currents of the order of 10^{-15} amperes.

10 The two-tube balanced circuit is a Wheatstone bridge circuit in which the tubes form two of the arms of the bridge. For all changes, except for 15 the external voltage impressed on one of the grids, the galvanometer must read zero for balanced conditions. The balance of a simple Wheatstone bridge does not depend on the current in the battery circuit. However, the variations in the battery circuit alter the filament current, grid bias, and plate voltage which in turn change the plate-filament resistance of the tubes. But if identical tubes are used, the same voltages impressed on both tubes, and the same current passed through 20 both filaments, then the plate-filament resistances will change together, and by suitable adjustments of the other resistances of the circuit, the bridge can be made to remain balanced in spite of battery circuit fluctuations.

25 30 The circuit shown in Fig. 1 is a single electron tube balanced circuit employing an electron tube shown at 1, having an anode at 2, a cathode at 3, a screen grid at 4, and a control grid at 5, as elementary parts thereof. The anode circuit comprises resistances numbered 6, 7, and 8 connected in series to the screen grid 4 and resistance numbered 9 connected therefrom to the cathode 3. I provide a galvanometer 10 and standard cell 12 connected in shunt with resistances 6 and 7 respectively. The source of potential shown at 14 is applied through variable resistance numbered 15 to the junction of resistances indicated at 6 and 7, and the cathode through resistance numbered 16. Resistance numbered 17 is connected 40 to the control grid and to the cathode through resistance shown at 16. The input is impressed across resistance shown at 17 and the output, in this case, is connected to the galvanometer.

45 50 This circuit may be considered as a Wheatstone bridge arrangement in which: resistance shown at 7 constitutes one leg; resistance numbered 8, in series with resistance 9 paralleled with the internal resistance of the tube between cathode and screen grid, a second leg; the internal resistance between cathode 3 and anode 2 of the tube, the third leg; and resistance shown at 6, the fourth leg. The former two legs carry the filament current I_0 , and the latter two legs carry the anode current I_1 . The input applied to the control grid 60 and cathode serves to vary the current in the anode-cathode leg of the bridge. I shall refer now to the letter designations in Fig. 1 to facilitate the use of equations. The dry cell E causes the potential balance across the galvanometer to 65 depend on I_0 if everything in the circuit remains constant. But the plate current I_1 fluctuates with the grid and plate potentials and the filament current. As these all fluctuate with I_0 , they also cause the potential balance across the galvanometer to depend on I_0 . Now as there are two influences on the balance depending on I_0 , they can be made to neutralize each other for all values of I_0 by properly adjusting the resistances of the circuit.

70 75 The values of the two resistances R_0 and R_1

depend upon the characteristics of the tube and circuit. The simplest way to determine this dependence is to regard the galvanometer, the cell E, and the resistances R_0 and R_1 as a Dowling zero shunt. When a current I_0 is passing through R_0 , then the requirement for no current through the galvanometer is:

$$R_0 I_0 - E = I_1 R_1 \text{ or } R_1 = (R_0 I_0 - E) / I_1 \quad (1)$$

Now for the circuit to be balanced for a change 10 ΔI_0 in I_0 and a corresponding change ΔI_1 in I_1 , the following equation must hold:

$$R_0 (I_0 + \Delta I_0) - E = R_1 (I_1 + \Delta I_1) \quad (2)$$

Substituting for R_1 from (1),

$$R_0 (I_0 + \Delta I_0) - E = (R_0 I_0 - E) (I_1 + \Delta I_1) / I_1 \quad (1.5)$$

$$R_0 \left(I_0 + \Delta I_0 - I_0 - \frac{I_0 \Delta I_1}{I_1} \right) = E \left(1 - 1 - \frac{\Delta I_1}{I_1} \right)$$

Cancelling and rearranging,

$$R_0 (I_1 \Delta I_0 - I_0 \Delta I_1) = -E \Delta I_1$$

or

$$R_0 = \frac{E \Delta I_1}{I_0 \Delta I_1 - I_1 \Delta I_0} = \frac{E}{I_0 - I_1 \frac{\Delta I_0}{\Delta I_1}} \quad (3) \quad 25$$

The above is the value of R_0 for balanced conditions in terms of E, I_1 , I_0 and the slope of the I_1 vs. I_0 characteristics. R_1 is then determined by Equation (1).

If E is constant, it is evident that the characteristics must be such that the denominator is a constant for all values of I_0 in order that R_0 can be a constant. By putting the denominator in differential form, equating it to a constant and solving the differential equation, we obtain the characteristics of I_1 vs. I_0 necessary to have R_0 a constant as follows:

$$I_0 - I_1 (dI_0/dI_1) = k_1 \quad (4) \quad 40$$

$$I_1 (dI_0/dI_1) = I_0 - k_1$$

$$\int \frac{dI_0}{I_0 - k_1} = \int \frac{dI_1}{I_1} \quad 45$$

$$\log (I_0 - k_1) = \log I_1 + \log k_2$$

$$\log (I_0 - k_1) = \log k_2 I_1 \quad (5)$$

$$I_0 = k_2 I_1 + k_1$$

50 Equation (5) is the general equation of a straight line. Therefore, if the portion of the characteristics near the operating value of I_0 is straight, the circuit will balance and remain balanced.

It is interesting to determine how critical the 55 value of R_0 is. Consider R_0 to be incorrect by an amount ΔR_0 . Then substituting in Equation (3) we have the incorrect value:

$$R_0' = E \Delta I_1 / (I_0 \Delta I_1 - I_1 \Delta I_0) + \Delta R_0 \quad 60$$

and from Equation (1) $R_1 = (R_0' I_0 - E) / I_1$. The potential across the galvanometer when the current I_0 has changed to $I_0 + \Delta I_0$ will then be:

$$\Delta E = R_0' (I_0 + \Delta I_0) - E - R_1 (I_0 + \Delta I_0) \quad (6) \quad 65$$

By substituting the values for R_0' and R_1 , we obtain

$$\Delta E = \Delta R_0 [\Delta I_0 - (I_0 / I_1) \Delta I_1] \quad (7)$$

Just how critical the value of R_0 is, thus depends also upon the I_1 vs. I_0 characteristics. If 70 the characteristics are such that

$$\Delta I_0 / \Delta I_1 = I_0 / I_1 \quad (8)$$

then ΔE is zero irrespective of ΔR_0 , hence any value of R_0 in this case will balance the circuit. 75

But the more $\Delta I_0/I_1$ deviates from I_0/I_1 , the more critical the value of R_o becomes. Equation (7) also shows that R_o can be determined experimentally. For R_o too large, ΔR_o is positive; hence, the galvanometer current will change in the positive direction with increase of I_0 . For R_o too small, ΔR_o is negative and, therefore, the galvanometer current will change in the negative direction with increase of I_0 . By changing I_0 and noting the deflection of the galvanometer, a value of R_o can be found for which changes in I_0 produce no change on the galvanometer.

The first experiment is the determination of the I_1 vs. I_0 characteristics of several pliotrons connected as in Fig. 3. Fig. 2 shows the characteristics of four similar pliotrons with $R_2=13.6$ ohms and $R_3=18.1$ ohms. The characteristics shown at 18 and 19 with these resistances are very straight in the operating region (110 milli-ampères). They, therefore, fit the theoretical conditions for balancing. The characteristic shown at 21 is practically straight at 110 milli-ampères; so it also fits the condition for balancing. The characteristic shown at 20 is considerably more curved than the other three, and consequently this tube should be more difficult to balance than the others.

The circuit of Fig. 3 is generally similar to that of Fig. 1. The resistance across the input at 17 is replaced in Fig. 3 by a cell 23 which may be connected or disconnected by the switch shown at 24. A radioactive ionization cell at 25, in series with battery shown at 26, is also connected in the control grid circuit of Fig. 3. Resistance at 16 in Fig. 1 is omitted in Fig. 3.

The correct value of R_o for any one of these tubes is determined experimentally by changing R in Fig. 1 or Fig. 3 and noting the direction of deflection of the galvanometer, as described in the foregoing theory. The degree to which the circuit is balanced is determined by noting the back and forth drift which a high sensitivity galvanometer will make, due to natural battery voltage fluctuations, or by varying I_0 and noting the galvanometer change. It was found that the tubes of 18 and 19 could be easily balanced and would remain balanced, and that the tube of 21 could be balanced and was stable. On the other hand, the tube of 20 was difficult both to balance and to keep balanced. These results correspond with what was to be expected from the theory and the I_1 vs. I_0 characteristics of the tubes. It is probably possible to change the values of R_2 and R_3 and obtain an I_1 vs. I_0 characteristic for the tube of 20 which will be straight at some workable value of I_0 . It should also be noted that the slope of the 18 and 19 curves approaches more nearly the conditions of Equation (8) than that of 21, so that R_o is less critical for 18 and 19 than for 21, which accounts for the experimental fact that the tubes of 18 and 19 are more easily balanced than the tube of 21.

The amount of variation in the circuit which can be balanced was determined for the tube of 18 as follows: The current I_0 was changed 10% after the circuit had been balanced. This change produced only a few mm. deflection on the galvanometer which was of a sensitivity about 10^{-8} amperes per mm. The large range in fluctuation of the battery current which can be balanced is indicated by this experiment.

The choice of circuit Fig. 1 or Fig. 3 depends upon the magnitude of the current to be read and the time requirement for the reading. The pliotron and galvanometer arranged as in circuit

Fig. 1 form a galvanometer type of system, which will read currents down to 5×10^{-14} amperes. The galvanometer can be made critically damped for resistance R_1 and R_o by means of a damping frame. With this refinement and proper shielding, this set-up is as stable and constant as a galvanometer of a sensitivity 10^{-10} amperes per mm. 5

The pliotron and galvanometer arranged as in circuit Fig. 3 with the cell at 25 omitted, form an easily set-up electrometer type of system. Any currents too small to be read on a galvanometer down to 10^{-15} amperes are most easily read by this set-up. It is limited to steady currents, because the current is measured by the rate of drift method, but this system can be set up in a short time with ordinary laboratory rheostats, a set of lead cells E_b , not necessarily specially conditioned, and a good dry cell E . The resistance R_o can be adjusted to its proper value for balancing as closely as desired. The larger currents are very easily measured, and currents of 10^{-15} amperes can be measured with just ordinary precautions of insulation and shielding. In either this or the first circuit, E can be a standard cell, as only currents of galvanometer magnitude pass through it, and R_1 can be adjusted so that no current is ever taken from the cell. For a permanent set-up, E is a standard cell, R_o , R_2 , and R_3 are permanent resistances, and the galvanometer is critically damped. 25

For the measurement of currents smaller than 10^{-15} amperes, it is desirable to neutralize the internal grid current of the tube which is of this order of magnitude. To accomplish this, the small radioactive ionization cell, shown at 25, is placed in the circuit and the following adjustments are made: With the key at 24 closed, R_o is adjusted until the circuit is balanced close enough for currents of the magnitude which are 40 to be measured. With no input current, key 24 is then opened and the cell 25 adjusted until the drift due to the grid current is neutralized by the leak through the cell. 35

The grid current is very nearly constant with change of grid voltage at -4 volts for this pliotron, and if the ionization cell 25 is at saturation voltage, the leak through cell 25 will not change with the grid voltage. The voltage on the grid, therefore, will be built up only by the 50 input grid current. 45

After the circuit is adjusted, the rate of drift method, just as in the unneutralized set-up, is applied to measure the very small currents. With good shielding and the temperature of the tube constant, the circuit was found to be sufficiently stable to measure currents of the order of 10^{-16} amperes. 55

The requirement for balancing a single tube with this circuit is that a portion of the filament plate current characteristic must be straight. The length of this straight portion determines the range of external fluctuations that can be balanced. This requirement is usually fulfilled for normal operating conditions. This one-tube circuit affords so simple a means of balancing external tube variations that it is as easily set up as an unbalanced circuit, will operate much more satisfactorily, and with refinements, will balance as closely as the two-tube circuit. 60

The advantages over the two-tube circuit are: the elimination of the difficulty in balancing, of extra apparatus, and of the necessity of obtaining exactly similar tubes, which, from the characteristics shown here, are not readily procured. 75

The balancing in these circuits is accomplished by adjusting resistances R_o , R_1 , and voltage E in Fig. 3. Without voltage E , the circuit would not balance even though it appears the drop $R_o I_o$ could be made to balance drop $R_1 I_1$. This is not possible, as can be seen, by allowing E to equal zero in the first equation after Equation (2), which will then cause R_o to cancel out of the equation and thereby eliminate the means of adjusting for balance. To have an additional voltage E in the circuit R_o , R_1 , and the output, is an essential feature of these circuits. Notice that the balance does not depend on the change of bias of the control grid, as there is no bias control in the balanced circuit of Fig. 3, and also that the screen grid was not used to balance the circuits shown where the additional cell E was inserted.

Fig. 4 shows the balanced single tube circuit of my invention connected to a single D. C. supply, indicated at 27. The cell voltage shown at 12 in Fig. 3, is replaced by the voltage drop across the resistance shown at 28. The output meter at 29, may be the galvanometer shown at 10 of Fig. 3 or any device to be operated by the amplified input current. The voltage on the screen grid in this circuit is less than the voltage on the anode by the drop across resistance shown at 30.

Fig. 5 is a diagrammatic sketch of the circuit of my invention wherein the screen grid potential is equal to the anode potential.

Fig. 6 shows a variation of the circuit of my invention wherein batteries are replaced in the circuit as shown at 38, 39 and 40. The screen grid potential is equal to the anode potential and the respective currents are balanced.

Fig. 7 illustrates another variation of the circuit of my invention wherein the plate potential is less than the screen grid potential by the potential drop across resistance 41.

Fig. 8 shows a variation of the circuit of Fig. 7 wherein batteries are replaced in the circuit, as shown at 40 and 42. The screen grid potential is greater than the anode potential by the voltage in the battery at 42 between the anode tap at 43 and the screen grid terminal at 45.

Fig. 9 shows the circuit of Fig. 4 adapted for connection to an alternating current power source indicated at 31. A second balanced circuit is connected to the output of the single stage shown in Fig. 4 for further amplification of the input. Primed reference numbers in the second electron tube circuit denote elements similar to the parts of the first electron tube circuit which are similarly numbered. Alternating or pulsating direct current can be amplified in this arrangement wherein inductive coupling is employed between the stages, as shown at 34, and a single source of anode potential, shown at 32, is connected to the anode of each tube. The screen grid voltage is less than the anode voltage by the drop across resistance shown at 30.

Fig. 10 shows the circuit of Fig. 9 but employing separate anode supply sources for each tube, as shown at 35 and 36. This permits direct connection of the output of the first stage, to the input of the second stage, as indicated at 37, and thereby the amplification of steady direct currents as well as alternating currents. Primed reference numbers in the second electron tube circuit denote elements similar to the parts of the first electron tube circuit which are similarly numbered. The voltage on the screen grid is

less than the voltage on the anode by the drop across resistance shown at 30.

Fig. 11 is a diagrammatic sketch of the balanced amplifier of my invention applied to a circuit containing a photo-electric device shown at 46, in which the phototube is not subjected to variations of line voltage.

The circuits of my invention show methods of taking the output of an electron tube circuit from between the anode and a grid, which is useful not only for balancing and stabilizing the tube circuit, but as a form of amplifier circuit to be used for any purpose where direct or alternating currents or voltages are to be amplified. The circuits of my invention comprise a network of resistances and the balancing is accomplished by the network itself, permitting amplification of a given input independent of its frequency or phase.

The method of taking the output from anode and a grid results in a higher degree of amplification than heretofore obtained besides balancing the circuit.

The voltage indicated as 12 in the drawings and as "E" in the equations is an essential characteristic of those circuits as described hereinbefore, especially by reference to the equation following Equation (2). In circuits wherein this voltage is dispensed with, a voltage drop or other equivalent means is substituted.

Wherever in the specification and claims I have referred to the screen grid of the electron tube, I desire that it be understood that any grid element additional to the control grid may be employed and is intended to be included by the said term "screen grid". Either grid of a pentode may be employed in the circuit arrangement set forth herein. The circuits will operate with any tube employing a grid between the filament or cathode and the control grid.

The measurement of minute currents and voltages is but one application of the amplifying property of the stabilized circuit of my invention. Such a circuit may be used as a relay, or in line wire systems and circuits as a repeater or booster and in many other uses which require substantial and undistorted increase of the energy impressed on the input of the amplifying device.

Although I have described my invention in certain of its preferred embodiments, I desire that it be understood that my invention is not to be limited thereby but may be modified in arrangement and no limitations are intended other than are imposed by the scope of the appended claims.

What I claim as new and desire to secure by Letters Patent of the United States is as follows:

1. In an electron tube circuit, an electron tube device comprising an anode, a cathode, a control grid and a screen grid, an output circuit comprising a plurality of variable resistance elements connected in series between said anode and said cathode, an input circuit connected between said control grid and said cathode, indicating means, a source of constant voltage, said indicating means and said constant voltage source connected in series, said series combination connected in parallel with two of said variable resistance elements connected in series, a second source of potential, one terminal of said second source of potential connected to the mid connection of said two variable resistance elements, the other terminal of said second source of potential connected to said cathode, means for externally varying

the potential on said control grid through said input circuit, and means including said source of constant voltage for normally maintaining a balance of potential across said indicating means.

5 2. In an electron tube circuit, an electron tube device comprising an anode, a cathode, a control grid, and a screen grid, a bridge arrangement comprising a plurality of variable resistance elements as two of the legs, the internal anode to 10 cathode resistance as another leg, the internal cathode to screen grid resistance in conjunction with a plurality of resistance elements as the fourth leg, a source of potential connected through another variable resistance element to 15 the cathode and the junction of the said first two legs, indicating means connected to the junctions of the legs opposite junctions connected to said source of potential, means for producing a balance of potential across the terminals of said 20 indicating means in said bridge arrangement and means for externally varying the current in one of said legs, said external variation thereby affecting said indicating means.

3. In an electron tube circuit, an electron tube 25 device comprising an anode, a cathode, a control grid and a screen grid, a circuit comprising a plurality of variable resistance elements connected in series between said anode and said cathode, an indicating device and a source of potential difference connected in series between said anode and 30 a point in said series of resistance elements, means for supplying potential for said anode and said screen grid, an input circuit comprising a source of potential and a switch connected in 35 series between said cathode and said control grid, said input circuit also comprising, in parallel with said series, a radioactive ionization cell and a second source of potential connected in series, said radioactive ionization cell acting to neutralize 40 the internal control grid-cathode current of said electron tube device, and means for impressing minute electrical values on said input circuit, the potentials on the terminals of said indicating device being normally balanced whereby 45 said minute electrical values may be measured by the degree of displacement of said balance.

4. In an electrical measuring instrument, an electron tube including a cathode, a control grid, a screen grid and an anode, an input circuit connected with said control grid and cathode, an output circuit connected between said anode and said cathode, a measuring instrument connected in said output circuit, a resistor disposed in said output circuit in series with said measuring instrument, a separate resistor connected between said screen grid and the terminal of said measuring instrument connected with said first mentioned resistor, and a potential supply circuit for said electron tube circuit extending from a source 50 of potential to one side of said cathode, a pair of resistors, a connection between the other side of said potential source with the junction of said pair of resistors, a connection between the end of one of said resistors and said anode, and a connection between the end of the other of said resistors with the resistor in the said output circuit at the terminal thereof connected with said cathode, whereby a balance of potential across the terminals of said measuring instrument is normally maintained and minute electrical values, impressed on said input circuit, are measured on said measuring instrument.

5. An electrical measuring instrument including an electron tube having a cathode, a control grid, an anode and a screen grid, a measuring in-

strument, a source of potential, a series circuit for supplying power from said source to said cathode, anode, and screen grid, comprising a multiplicity of series connected resistors, a connection from a point between two of said resistors to said screen grid, a resistor in said connection, a separate resistor connected between a point in said series circuit and said anode, and connections between the opposite ends of said last mentioned resistors with said measuring instrument.

6. An electrical measuring instrument containing one or more electron tubes each having an anode, a cathode and at least one grid electrode, all electrodes of the same tube being supplied by one source of power, a series circuit including a plurality of impedance elements interconnecting said anode and cathode electrodes, and means whereby the drop in potential across an impedance or impedances carrying the current of one electrode can be balanced by the algebraic sum of a drop of potential across an impedance carrying current directly from said source of power and another potential difference produced either by the drop in potential across an impedance carrying the current of any other electrode of the same tube or by any separately introduced source of potential of any kind.

7. An electrical measuring instrument comprising an electron tube having anode, cathode, and a plurality of grid electrodes, a source of power for said instrument, a balanced circuit connected with the output of said electron tube, said balanced circuit including an impedance element carrying the current of said anode electrode, a second impedance element carrying current directly from said source of power, and a third impedance element carrying the current of one of said grid electrodes, the algebraic sum of the potential drops across said impedance elements being zero for a balanced condition of said circuit, means for impressing the quantity to be measured on another of said grid electrodes, an indicating device connected in said circuit and operable under conditions of unbalance of said circuit to indicate the degree of unbalance of said circuit and measure the value of the electrical quantity producing said unbalance.

8. An electrical measuring instrument as defined in claim 7 in which the means for impressing the quantity to be measured comprises a photo-electric device having an anode and a light sensitive cathode electrode, said anode being connected to the positive terminal of the source of power, and said light sensitive cathode being connected to the control grid for producing variations in the balance of the output circuit in accordance with light variations on said light sensitive cathode.

9. An electrical measuring instrument comprising an electron tube having anode, cathode, and a plurality of grid electrodes, a source of power for said instrument, a balanced circuit connected with the output of said electron tube, said balanced circuit including an impedance element carrying the current of said anode electrode, a second impedance element carrying current directly from said source of power, and a separate source of potential, the algebraic sum of the potential drops across said impedance elements and the separate source of potential being zero for a balanced condition of said circuit, means for impressing the quantity to be measured on another of said grid electrodes, an indicating device connected in said circuit and operable under conditions of unbalance of said circuit to indicate the

degree of unbalance of said circuit and measure the value of the electrical quantity producing said unbalance.

10. The method of balancing potentials across the terminals of an indicating device in the output of a single electron tube which comprises opposing a drop in potential due to the current flowing to one electrode of said tube by the algebraic sum of a drop in potential due to current flowing 10 directly from a source of power and a separate potential difference produced either as a drop in potential due to the current flowing to another electrode of said tube or in a separately introduced source of potential.
15. 11. The method of balancing potentials across the terminals of an indicating device in the output of a single electron tube which comprises opposing a drop in potential due to the current flowing to one electrode of said tube by the algebraic sum of a drop in potential due to current flowing 20 directly from a source of power and a separate potential difference produced as a drop in potential due to the current flowing to another electrode of said tube.
25. 12. The method of balancing potentials across the terminals of an indicating device in the output of a single electron tube which comprises opposing a drop in potential due to the current flowing to one electrode of said tube by the algebraic sum of a drop in potential due to current flowing 30 directly from a source of power and a separate potential difference produced in a separately introduced source of potential.
13. The combination of an electron discharge device having a cathode, a grid element, a control grid element and an anode, a circuit including a source of voltage connected with said cathode, means for obtaining from said circuit a voltage for said anode, means for obtaining from said circuit a voltage for said first grid element, an electromagnetic instrument connected between said anode and said first grid element, and means connected between said latter means and said first grid element for compensating the changes in 45 voltages supplied by said circuit.
14. The combination of an electron discharge device having a cathode, a grid element, a control grid element and an anode, a circuit includ-

ing a source of voltage connected with said cathode, means for obtaining from said circuit a voltage for said anode, means for obtaining from said circuit a voltage for said first grid element, an electromagnetic instrument connected between 5 said anode and said first grid element, and means connected between said latter means and said first grid element for compensating the changes in voltages supplied by said circuit through a range of at least $\pm 10\%$ change. 10

15. In a measuring instrument, the combination of an electron discharge device having a cathode, an anode and two grid elements, an input circuit connected between said cathode and one of said grid elements, a circuit including a 15 resistor connected between said cathode and said anode, an indicating device and a resistor connected in series between said anode and an intermediate point on said first resistor, one terminal of said indicating device being connected to said 20 anode, and a connection from said other grid element to a point between said indicating device and said second resistor.

16. In a balanced circuit, the combination of an electron discharge device having a cathode, an 25 anode, a control grid element and a grid element, a resistor and a source of voltage connected in series with said cathode, a resistor connected between said source of voltage and said anode, an electromagnetic instrument and a resistor connected between said anode and an intermediate 30 point on said first resistor, and a connection from said first grid element to said indicator and said last-mentioned resistor.

17. In a measuring circuit, the combination of 35 an electron discharge device having a filamentary cathode, a space charge grid, and an anode, a resistor and a source of voltage connected in series with said cathode, a resistor connected between said anode and said source of voltage, an 40 electromagnetic instrument connected between said anode and an intermediate point on said first resistor, a connection from said space-charge grid to said intermediate point on said first resistor, and a resistor connected in series with said instrument and said connection for compensating the changes in voltage of said source of voltage. 45
